(57) **CLAIM**

The ornamental design for track pliers, as shown and described.

DESCRIPTION

FIG. 1 is a perspective view of track pliers according to the present invention.

FIG. 2 is a front elevation view of the track pliers of FIG. 1.

FIG. 3 is a rear elevation view of the track pliers of FIG. 1.

FIG. 4 is a side elevation view of the track pliers of FIG. 1.

FIG. 5 is another side elevation view of the track pliers of FIG. 1.

FIG. 6 is a bottom plan view of the track pliers of FIG. 1; and,

FIG. 7 is a top plan view of the track pliers of FIG. 1. The broken lines in the drawings illustrate portions of the track pliers that form no part of the claimed design.
